(57) **CLAIM**

The ornamental design for a kitchen utensil, as shown and described.

DESCRIPTION

FIG. 1 is a top-front-left isometric view of a kitchen utensil in accordance with the present design;

FIG. 2 is a top-rear-right isometric view thereof;

FIG. 3 is a front view thereof;

FIG. 4 is a rear view thereof;

FIG. 5 is a right side view thereof;

FIG. 6 is a left side view thereof; and,

FIG. 7 is top view thereof.

The broken lines illustrate features of the kitchen utensil that form no part of the claimed design.
